(57) **CLAIM**

The ornamental design for an electric unicycle, as shown and described.

DESCRIPTION

1.1 is a right side elevation view of an electric unicycle showing our new design;

1.2 is a left side elevation view thereof;

1.3 is a front elevation view thereof;

1.4 is a rear elevation view thereof;

1.5 is a top plan view thereof;

1.6 is a bottom plan view thereof; and

1.7 is a top, front, and right side perspective view thereof.

The broken lines shown in the drawings illustrate portions of the electric unicycle that form no part of the claimed design.
